H. H. & H. T. HIPWELL.
PORTABLE FLASH LIGHT.
APPLICATION FILED MAR. 25, 1915.

1,144,201.

Patented June 22, 1915.

UNITED STATES PATENT OFFICE.

HARRY H. HIPWELL AND HARRY T. HIPWELL, OF PITTSBURGH, PENNSYLVANIA.

PORTABLE FLASH-LIGHT.

1,144,201.

Specification of Letters Patent. Patented June 22, 1915.

Application filed March 25, 1915. Serial No. 16,968.

To all whom it may concern:

Be it known that we, HARRY H. HIPWELL and HARRY T. HIPWELL, citizens of the United States, residing at N. S. Pittsburgh, 5 in the county of Allegheny, State of Pennsylvania, have invented a new and useful Portable Flash-Light, of which the following is a specification.

The present invention appertains to a 10 portable flash light, and aims to provide a portable flash light of such formation that it may be conveniently carried in the vest or coat pocket, the flash light simulating a fountain pen or pencil in contour, whereby 15 it may be conveniently carried and handled.

It is the object of the present invention to provide a pocket flash light having improved details of construction, to enhance the utility and efficiency thereof, and which 20 is particularly useful in view of the pencil or fountain pen formation of the case.

Among its specific objects, the invention aims to provide novel circuit controlling means, novel means for insulating the 25 battery, and novel means for holding the sections or parts of the case assembled so that they may be slid or moved relative to one another for controlling the circuit.

It is also within the scope of the invention to provide a pocket flash light having the above mentioned features, and which is 30 comparatively simple and inexpensive of construction, as well as being serviceable, convenient, practical and efficient in its use.

With the foregoing and other objects in view which will appear as the description proceeds, the invention resides in the combination and arrangement of parts and in the details of construction hereinafter described and claimed, it being understood 40 that changes in the precise embodiment of the invention herein disclosed can be made within the scope of what is claimed without departing from the spirit of the invention.

The invention is illustrated in the accompanying drawing, wherein:

Figure 1 is a side elevation of the improved flash light. Fig. 2 is a longitudinal section thereof taken on the line 2—2 of Fig. 50 1. Figs. 3 and 4 are cross sectional views taken on the lines 3—3 and 4—4, respectively, of Fig. 2.

In carrying out the invention, the case embodies a metallic tube or barrel 1, into which the battery or cell 2 is slipped so as to fit snugly therein. One end of the tube or

barrel 1 is provided with a narrow inturned annular lip or flange 3, and an annular insulator 4 is fitted within the said end portion of the tube 1 and seats against the lip 3. The lip 3 overlaps the insulator 4 so as to terminate short of the central aperture or opening of the insulator, and the central terminal or pole member 5 of the battery or cell 2 projects into or partially through the 65 central aperture or opening of the insulator 4. This insulator 4 bears against the lip 3, while the respective end of the battery or cell 2 bears against the insulator 4, it being noted that the insulator 4 insulates the central terminal or pole member 5 of the battery from the tube 1, and especially the lip 70 3 thereof.

A detachable plug 6 is engaged within the other end of the tube 1, and carries a spiral 75 spring 8 which has its larger convolution secured within the plug 6, and which has its smaller convolution bearing against the respective end of the battery 2 to press the battery 2 yieldably against the insulator 4, 80 and whereby the battery is held in place. The spring 7 also acts as a conductor for electrically connecting the shell or other pole member of the battery 2 with the tube 1 of the case, the spring 7 and plug 6 being 85 metallic. The plug 6 is provided with lugs 8 engaged in bayonet slots 9 provided in the respective end portion of the tube 1, whereby the plug 6 may be locked in engagement with the tube, and may be readily attached 90 to and detached from the tube. When the plug 6 is removed, the battery 2 may be readily withdrawn for purpose of renewing or replacing the same when worn out.

The case embodies a second section or part 95 which is in the form of a metallic sleeve 10 sliding or telescoped over the end portion of the tube 1 having the lip 3. The tube 1 resembles the barrel of a fountain pen or pencil, while the sleeve 10 resembles the cap 100 of a fountain pen or pencil, whereby the case will have the appearance of a fountain pen or pencil, and may be conveniently carried in the coat or vest pocket, or the like.

A clip 11 is riveted or otherwise secured, 105 as at 12, to one side of the sleeve or cap 10 and projects toward the remote end of the tube 1. This clip 11 resembles the clip of a fountain pen or pencil, whereby the clip 11 may be engaged over the edge portion of the pocket in which the flash light is inserted and so that the device may be con- 110

veniently carried and held within the pocket. The clip 11 is resilient or flexible in the manner of an ordinary fountain pen or pencil clip. The exterior parts of the tube 1, sleeve 10, clip 11 and plug 6 are preferably nickel plated or otherwise finished for purpose of wear and appearance.

The tube 1 and sleeve 10, or the sections of the case, are provided with interengaging means for limiting the sliding movement of the sleeve or cap 10 upon the tube 1, and to this end, the sleeve 10 is provided underneath the clip 11, with an instruck resilient tongue 13 projecting toward the end of the tube 1 having the lip 3, and the tube 1 is provided within the sleeve 10 with a longitudinal slot 14 receiving the free portion of the tongue 13. The slot 14 is of limited length to limit the sliding or longitudinal movement of the sleeve 10.

The outer or free end of the sleeve 10 is provided with a dished reflector 15 which is plated or polished, and which is provided with a central inwardly projecting threaded socket portion 16 for receiving the threaded plug 17 of an incandescent lamp 18. The globe 19 of the lamp 18 is disposed within the reflector 15. The incandescent lamp is thus carried by the end of the case, or by the end of the sleeve or cap 10 which is mounted slidably upon the tube 1.

The sliding movement of the sleeve 10 upon the tube 1 is utilized for controlling the circuit, the insulated terminal or contact member 20 of the lamp 18 projecting inwardly and being in alinement with the terminal or pole member 5 of the battery, whereby when the sleeve or cap 10 is slid downwardly upon the tube 1, the terminal or contact member 20 of the lamp is brought into engagement with the terminal or pole member 5 of the battery, for closing the circuit through the lamp 18, case 10¹, and spring 7 to the opposite pole of the battery.

The circuit is normally opened by means of a coiled wire expansion spring 21 disposed within the sleeve or cap 10 between the lip 3 and insulator 4 and the annular socket between the walls of the sleeve 10 and reflector 15. When the sleeve 10 is released, the spring 21 will throw the same outwardly or upwardly to open the circuit.

The present flash light may be conveniently carried in the pocket or similar receptacle, and may be conveniently manipulated. To light the lamp, it is only necessary to slide the sleeve or cap 10 downwardly or inwardly upon the tube or barrel 1, which will bring the lamp into contact with the battery. The component parts of the flash light may be readily assembled. Thus, the insulator 4 may be readily slipped into the tube 1 from that end opposite the lip 3, when the battery 2 and plug 6 are removed, and the battery 2 then being in-

serted into the tube 1, will force the insulator 4 into position, and the insulator will also receive the terminal or pole member 5 of the battery for insulating the same from the case. The spring 21 may be readily inserted into the sleeve or cap 10 when the same is detached from the tube 1, and it is to be noted that when the cap 10 is forcibly slid upon the tube 1, the tongue 13 will spring outwardly to allow the sleeve to be moved into position, and when the sleeve is moved into proper position, the tongue 13 will spring into the slot 14 for limiting the longitudinal movement of the sleeve 10 and tube 1 relative to one another. The sleeve or cap 10 may be removed, this being readily accomplished by forcing the sleeve 10 and tube 1 together and turning the same relative to one another whereby the tongue 13 is sprung outward out of engagement with the slot 14, and in which event the sleeve and tube may be readily separated. It is to be noted that the tongue or member 13 of the cap 10 which engages the slot 14 of the tube 1, is located underneath the clip 11 so as to be concealed thereby, in order that the tongue 13 will not impair the appearance of the flash light, and cannot be readily detected. It is preferable to provide the inner end portion of the sleeve or cap 10 with one or more annular knurled corrugations or beads 22 whereby the sleeve or cap may be readily slid downwardly or inwardly before closing the circuit.

Having thus described the invention, what is claimed as new is:

1. A portable flash light embodying a tube for holding a battery, a sleeve slidable upon one end portion of the tube and having means at its outer end for receiving an incandescent lamp, whereby when the sleeve is slid inwardly it will bring the lamp into engagement with the battery, a clip secured to the sleeve for engaging the edge portion of a pocket, the tube having a longitudinal slot of limited length, and the sleeve having means underneath and concealed by the clip engaging said slot for limiting the movement of the sleeve relative to the tube.

2. A portable flash light comprising a case embodying a tube and a sleeve slidable upon one portion of the tube, a battery fitting snugly within the tube, the outer end of the sleeve having a lamp socket, an incandescent lamp engaged in said socket, one pole of the battery being connected electrically to the case, and the other pole of the battery being adapted to be engaged by one terminal of the lamp when the sleeve is moved inwardly upon the tube, the tube having a longitudinal slot and the sleeve having a portion working in said slot, and means for yieldably moving the sleeve outward relative to the tube for disengaging the lamp from the respective pole of the battery.

3. A portable flash light comprising a casting embodying a tube and a sleeve slidable upon one end portion thereof, the tube being adapted to hold a battery, said end of 5 the tube having an inturned annular lip, an annular insulator fitting within the tube and seating against said lip, and adapted to receive one pole member of the battery, and the outer end of the sleeve having means 10 for receiving an incandescent lamp whereby when the sleeve is moved inwardly it will bring the lamp into engagement with said pole member.
4. A portable flash light comprising a 15 metallic casing including a tube and sleeve slidable upon one end portion of the tube, said end of the tube having an inturned annular lip, an annular insulator fitting within the tube and seating against said lip, a 20 battery fitting within the tube and having
- one pole connected to the casing, the battery having another pole member fitting within said insulator, the sleeve and tube having interengageable means for limiting their relative movement, the outer end of the sleeve 25 having a lamp socket, a lamp engaged in said socket and arranged to contact with said pole member when the sleeve is moved inwardly to establish a circuit through the lamp, and a spring within the sleeve for 30 yieldably moving the same outward to disengage the lamp from said pole member.

In testimony that we claim the foregoing as our own, we have hereto affixed our signatures in the presence of two witnesses.

HARRY H. HIPWELL.
